FUEL INJECTION DEVICE

Savarian Lemanski, Detroit, Mich.

Application October 15, 1949, Serial No. 121,479

5 Claims. (Cl. 103—2)

1

This invention relates to a device for injecting fuel into the fuel compression space above the piston of an internal combustion engine and the object of the invention is to provide an injector in which a fuel and air mixture is discharged into the compression space provided in the head of the cylinder at the time ignition of the fuel takes place.

These and other features of the invention are hereinafter more fully described and claimed and a fuel injection device embodying my invention is shown in the accompanying drawing in which—

Fig. 1 is a sectional view showing my improved fuel injection device in conjunction with a cylinder, fragmentarily shown.

Fig. 2 is a section taken on line 2—2 of Fig. 1.

Fig. 3 is a fragmentary section taken on line 3—3 of Fig. 1.

Fig. 4 is a section taken on line 4—4 of Fig. 1.

Fig. 5 is a section taken on line 5—5 of Fig. 1.

Figs. 6 and 7 are diagrammatic views illustrative of the means by which the volume of the injected fuel may be varied.

Fig. 8 is a section taken on line 8—8 of Fig. 1.

Fig. 9 is a section taken on line 9—9 of Fig. 8 showing the form of the fuel discharge aperture leading to the head of the piston.

The inner surface of the head 1 of the engine cylinder has a recess 2 which is tapered as shown and terminates in an aperture 3 aligned with an aperture 4 in the wall of the fuel injector housing 19.

The engine piston 5 is reciprocable in the engine cylinder 1. The plunger 5a of the fuel injector, reciprocal in the chamber 6a of injector housing 19, has a longitudinal central recess 6 of circular cross section in the upper end thereof. Cylindrical disc 20 is immovably seated within injector housing 19 at its upper end and has a centrally depending stem 22 which has a pair of plane surfaces 7 and 8 on its opposite sides throughout its lower half as shown in Fig. 3 and in Fig. 1, and a second pair of plane surfaces 7 and 8 throughout its upper one-half arranged at a 90 degree angle with respect to said first plane surfaces, as shown in Figs. 4 and 8.

Adjacent the upper end of the plunger 5a is a ring 9 having a triangularly shaped aperture 10 in one side thereof which, in the position of the parts shown in Figs. 1 and 2, opens to the said aperture 4 in housing 19.

The plunger 5a has a peripheral groove in which a ring 12 is positioned as shown in Figs. 1 and 2, and further has a series of peripheral

grooves 13 to which lubricating oil is supplied by means of a conduit 14, Fig. 1.

The fuel and air mixture inlet pipe is indicated at x in Figs. 2 and 4 for delivering an air and fuel mixture under pressure to chamber 6a at the upper end of housing 19 as shown in Fig. 2. This mixture, upon upward movement of plunger 5a, is forced downwardly into elongated recess 6 between its wall and the outer surface of the disc stem 22, and thence through the radial passage 21 in plunger 5a for connection with the triangular outlet aperture 10 in sleeve 9.

Thus reciprocation of plunger 5a intermittently forces the fuel mixture through outlet aperture 10 and passage 4 into passage 3 of the cylinder combustion chamber as indicated in Fig. 1.

It is apparent from Fig. 2 that fuel accumulated in the lower end of recess 6 will be similarly forced upwardly and out through the radial passage 21 when said plunger is moved upwardly. Thus it might be said that the portion of chamber 6a above plunger 5a in Fig. 2, and the portion of the slot 6 below stem 22 are pumping chambers within which a fuel mixture may accumulate. Upon upward movement of the plunger 5a the volume of both said pumping chambers is progressively decreased to zero with the result that the said fuel mixtures from said chambers will be injected or forced outwardly through the radial slot 21 and the aperture 10 and through the passages 4 and 3 shown in Fig. 1, for delivery into the upper end of cylinder head 1.

The plunger 5a is movable in one direction in the chamber 6a of the fuel injector housing 19 by means of a cam element 5b, fragmentarily shown, and which is connected with the engine shaft in the manner usual with an internal combustion engine. Said plunger is movable in the opposite direction by the coil spring 15. The upper end of said spring engages under a shoulder in the housing 19, and the opposite end of said spring is positioned in a recess 15a provided therefor in the cap 16 which is threaded upon the lower end of plunger 5a as shown in Fig. 1.

A fuel discharge conduit is also indicated at 1c in Figs. 2 and 4 for delivering a fuel mixture to the interior of engine starting chamber 1b on the cylinder head 1, which has a spark plug 8, fragmentarily shown in dotted lines, projected thereinto and which is connected in an ignition circuit in a conventional manner.

The valve 1d is normally seated in an aperture provided therefor in the bottom of chamber 1b. The valve 1d is manually closed after the engine

is started. Thereafter the heat developed by the compression of the fuel mixture ignites the same.

In starting the engine it is necessary that the plunger 5a be rotated sufficiently so that its radial passage 21 will be in communication with the secondary outlet passage 1c which conducts a fuel mixture to the starting chamber 1b. For this purpose the aperture 10 in the ring 9 is rotated into alignment with the passage or conduit 1c and fuel will discharge into the starting chamber 1b and will be ignited therein. The valve 1d will be opened so that the combustible mixture may expand within the upper end of the cylinder head 1 when ignited to thus start the engine.

The cap 16 secured to the lower end of plunger 5a has gear teeth 17 in its periphery and a toothed rack 18 engages said gear teeth and is connected with means, not here shown, for longitudinal adjustment.

In starting the engine, initial longitudinal adjustment of rack 18 rotates plunger 5a sufficiently that the fuel mixture from chamber 6a flows through outlet 10 and through the passage and conduit 1c into the starting chamber 1b. Thereafter the rack is returned to its initial position, repositioning the plunger 5a rotatively so that thereafter the flow of the fuel mixture through radial passage 21 and aperture 10 will be directed through the passage 4 in housing 19 and through a corresponding passage 3 to the interior of the combustion chamber shown in Fig. 1. The rack gear 18 may be adjusted regulating the position of plunger 5a and the effective area of the aperture 10 to thereby throttle or control the flow of said mixture through the triangular aperture 10 or a part thereof into the passage 4 of housing 19, as will be understood from the diagrammatic views Figs. 6 and 7. Fig. 6 indicates that with only a portion of the triangular aperture 10 in registry with passage 4 there will be a limited flow of combustible mixture whereas in Fig. 7 the greater portion of aperture 10 is in registry with the passage 4 with the result that there is an increased amount of combustible mixture delivered to the combustion chamber.

A conduit 14a is shown in Figs. 1 and 4 which is provided for supplying water or water vapor to the chamber 6a if desired for addition to the combustible mixture delivered thereto through the pipe x.

Having described my invention, reference should now be had to the claims which follow for determining the scope thereof.

I claim:

1. A fuel injection device comprising an elongated chambered housing having longitudinally spaced fuel mixture inlet and outlet passages, a reciprocal plunger within said housing intermittently spaced from one end of said housing defining a pumping chamber to which said inlet passage is connected, said plunger having an axial slot open at one end to said pumping chamber, said plunger having a radial fuel delivery passage connected at one end with said slot with its other end connected to said outlet passage, and a stationary stem depending from said housing and positioned down into said slot, its outer walls being so formed as to define longitudinal passageways along said stem interconnecting said pumping chamber and the closed end of said slot, said radial delivery passage having an enlarged outlet aperture of triangular shape at its outer end for delivering said mixture to said outlet passage, gear teeth on said plunger, and a longitudinally adjustable rack gear in mesh with said gear teeth for rotatably adjusting said plunger to regulate the effective area of said aperture.

2. A fuel injection device comprising an elongated chambered housing having longitudinally

spaced fuel mixture inlet and outlet passages, a reciprocal plunger within said housing intermittently spaced from one end of said housing defining a pumping chamber to which said inlet passage is connected, said plunger having an axial slot open at one end to said pumping chamber, said plunger having a radial fuel delivery passage connected at one end with said slot with its other end connected to said outlet passage, and a stationary stem depending from said housing and positioned down into said slot, its outer walls being so formed as to define longitudinal passageways along said stem interconnecting said pumping chamber and the closed end of said slot, said end of said stem being intermittently spaced from the closed end of said slot defining a secondary pumping chamber, whereby upon upward movement of said plunger said pumping chambers are progressively reduced in volume forcing the fuel mixture therefrom along said passageways and through said outlet passage.

3. A fuel injection device comprising an elongated chambered housing having longitudinally spaced fuel mixture inlet and outlet passages, a reciprocal plunger within said housing intermittently spaced from one end of said housing defining a pumping chamber to which said inlet passage is connected, said plunger having an axial slot open at one end to said pumping chamber, said plunger having a radial fuel delivery passage connected at one end with said slot with its other end connected to said outlet passage, a stationary stem depending from said housing and positioned down into said slot, its outer walls being so formed as to define longitudinal passageways along said stem interconnecting said pumping chamber and the closed end of said slot, said radial delivery passage having an enlarged outlet aperture of triangular shape at its outer end for delivering said mixture to said outlet passage, and means joined to said plunger for rotatably adjusting the same to regulate the effective area of said aperture.

4. A fuel injection device comprising an elongated chambered housing having longitudinally spaced fuel mixture inlet and outlet passages, a reciprocal plunger within said housing intermittently spaced from one end of said housing defining a pumping chamber to which said inlet passage is connected, said plunger having an axial slot open at one end to said pumping chamber, said plunger having a radial fuel delivery passage connected at one end with said slot with its outer end connected to said outlet passage, a stationary stem depending from said housing and positioned down into said slot, its outer walls being so formed as to define longitudinal passageways along said stem interconnecting said pumping chamber and the closed end of said slot, said radial delivery passage having an enlarged outlet aperture of triangular shape at its outer end for delivering said mixture to said outlet passage, gear teeth on said plunger, and a longitudinally adjustable rack gear in mesh with said gear teeth for rotatably adjusting said plunger to regulate the effective area of said aperture.

5. A fuel injection device comprising an elongated chambered housing having longitudinally spaced fuel mixture inlet and outlet passages, a reciprocal plunger within said housing intermittently spaced from one end of said housing defining a pumping chamber to which said inlet passage is connected, said plunger having an

axial slot open at one end to said pumping chamber, said plunger having a radial fuel delivery passage connected at one end with said slot with its other end connected to said outlet passage, a stationary stem depending from said housing and positioned down into said slot, its outer walls being so formed as to define longitudinal passageways along said stem interconnecting said pumping chamber and the closed end of said slot, said housing having a second outlet passage angularly disposed with respect to said first outlet passage, and means joined to said plunger for rotatably adjusting the same for selectively connecting said radial passage with said second outlet passage.
